The ornamental design for a suspended instrumentation system, as shown and described.

DESCRIPTION

FIG. 1 is a front view of the system;

FIG. 2 is top view of the system;

FIG. 3 is a side view of the system, the opposite side view being a mirror image thereof;

FIG. 4 is a rear view of the system;

FIG. 5 is a bottom view of the system; and,

FIG. 6 is a front view of another version of the system. The suspension rod is shown broken away to indicate indeterminate length.
